The ornamental design for a bandage, as shown and described.

DESCRIPTION

FIG. 1 is a top plan view of a bandage, showing my new design;

FIG. 2 is a bottom plan view thereof;

FIG. 3 is a right side elevational view with the left side being a mirror image thereof; and,

FIG. 4 is a front elevational view with the rear elevational view being a mirror image thereof.

The broken line showing of the bandage and of the bandage box in FIG. 1 is for illustrative purposes only and forms no part of the claimed design.
